E. H. LUNKEN

WINDOW SHADE

Filed June 17, 1919

UNITED STATES PATENT OFFICE.

EDMUND H. LUNKEN, OF CINCINNATI, OHIO.

WINDOW SHADE.

Application filed June 17, 1919. Serial No. 304,829.

To all whom it may concern:

Be it known that I, EDMUND H. LUNKEN, a citizen of the United States, and a resident of the city of Cincinnati, in the county of 5 Hamilton and State of Ohio, have invented certain new and useful Improvements in Window Shades, of which the following is a full, clear, and exact description, reference being had to the drawings accompanying this 10 specification.

My invention relates to window shades, and more particularly to shades adapted to enclose the whole or any part of the window either from the bottom or from the top of 15 the window opening.

Among other uses to which a window shade can be put, is to close the opening through the window from view, and yet permit air to come in at the sides of the shade. 20 Also, in many instances it is desirable to close the lower part of the window and perhaps some of the upper part, and yet permit light to come through the central portion thereof. In this latter way ventilation can 25 be had through the central portion of the window, persons are prevented from seeing into the room, and the light from above is considerably dimmed, within the room. There are also many other uses where the 30 shade may serve as a shutter, and ventilator, which are obvious.

It is the object of my invention to adapt the usual type of window shade to the new functions developed by my discoveries and 35 to do this in the simplest possible way, and with the fewest necessary changes and provision of new parts.

My objects and advantages, as will be noted I accomplish by that certain construction and arrangement of parts to be herein-after more specifically pointed out and claimed, wherein, a fitting is provided for the window frame, the catches removed from the usual window shade rollers, and a modified bar inserted instead of the usual stiffening lath, in the free end of the shade, and wherein also two shades are used, one mounted below the window opening and one above. 45

In the drawings,

Figure 1 is a front elevation of a window showing the shade in use.

Figure 2 is a side elevation thereof.

Figure 3 is a detail perspective of one of the frame fittings.

Figure 4 is a detail side elevation of the curtain roller and its attachment.

Figure 5 is an elevation of the bar employed in the free end of the shades.

Figure 6 is a perspective of a modified frame fitting.

The window, shown has a frame, with a sill 1, cap 2 and sides 3 and 4. The curtain rollers 5 and 6 for the cap and sill respectively of the window frame, are of the usual pattern in wide use at the present time, with 60 the exception that I prefer to inhibit the action of the catch which holds the roller from exerting tension on the roller, in the type of shade.

Thus one usual type of shade roller has a 70 dog or catch 6^a, which engages by gravity in a notch formed on the spindle of the roller. I so arrange the notch on the roller spindle that it is held in a downward position, whereby the dog will never form its 75 gravity engagement unless the curtain is removed so as to be wound up, or the spring tightened on the spindle.

The usual brackets for retaining the roller in position are used for the upper and lower 80 shades. Of these the bracket 7 (Figure 4) is shown retaining the roller 6 at the sill of the window frame, with this roller equipped with the shade 8. A like fitting is at the upper end of the window, near the cap there- 85 of, having the roller 5 and the shade 9.

The usual stiffening lath pieces are removed from the standard type of window shade, which is used with the rollers and the stiffening and retaining bar 10 inserted in the 90 free, hemmed ends 8^a and 9^a, respectively, of the two shades. These rods are made preferably stronger than the usual stiffening lath and have at their ends the extending pins 11, which protrude beyond the edges of 95 the shades.

At the desired number of points on each side of the window frame are mounted the flat double hooks 12, which may be of one piece, and have bases 13 to screw to the window frame. The hook portions should be of considerable width so as to readily receive the pins on the stiffening bars in the ends of the shades this width to be at least equal to double the width of one of the pins. 100

As so constructed the device operates as follows:—The user lifts or pulls down the shades as desired, and places the pins on the stiffening bars above or below the double hook fittings 12. Due to the spring being 110 constant on the rollers, there will always be a tension exerted against the shades, tending

to hold them against undue flapping, if the wind is free to enter the window due to the opening of the sash. For added ventilation, the hooks 12 may be provided with extended arms 14 and hooks 15, permitting an angled position of the shades (Figure 6).

Due to the width of the hooks, it makes no difference if the upper or lower shade is attached to any hook first since the pins can be pushed against the window frame thereby permitting the pins on the other shade to find a seat on the opposite hook. The width of the shades is, of course, not enough to rub against the hooks, and as described, the standard shade and roller are used with the minimum amount of alteration.

10 I do not desire to limit myself to the exact conformation of the hooks, or necessarily to the width thereof, neither do I wish to limit myself to the exact nature of the means employed to provide retaining pins at the free ends of the shades.

20 Having thus described my invention what I claim as new and desire to secure by Letters Patent is:—

25 1. In a window shading device, the combination with upper and lower shades for the cap and sill respectively of the window frame, of fittings mounted at the sides of the frame to simultaneously retain the free ends of both shades intermediate the window opening and adapted to hold the shades in lapped relation.

30 2. In a window shading device, the combination with a lower and upper shade having extending portions at the free ends thereof, of a retaining device for said free ends located along the window frame, and comprising a single hook element having hooks opening upwardly and downwardly and adapted to engage the extending portions of an upper and a lower shade simultaneously.

3. In a window shading device, the combination with a lower and upper shade having extending portions at the free ends thereof, of a retaining device for said free ends located along the window frame, and comprising a hooked element having hooks opening upwardly and downwardly, said hooks being of at least sufficient width to retain, side by side, two extending portions whereby each shade may be engaged in the hooks without displacement of the shade.

4. In a window shading device the combination with a lower and upper shade under constant tension, of stiffening bars in the free ends of the shades, and retaining hooks mounted at the sides of the window, said stiffening bars having extending pins at the sides of the shades and said hooks being open upwardly and downwardly, and the hook portions both upward and downward opening being of at least twice the width of the extending pins.

5. In a window shading device, the combination with upper and lower shades for the cap and sill respectively of the window frame, same being mounted close to the frame, of fittings mounted at the sides of the frame intermediate the cap and sill to retain the free ends of both shades, said fittings being extending from the frame to retain the shades at a sloping position.

6. In a window shading device, the combination with upper and lower shades for the cap and sill respectively of the window frame, same being mounted close to the frame, of fittings mounted at the sides of the frame intermediate the cap and sill to retain the free ends of both shades, said shades being under constant spring tension, said fittings being extended from the frame to retain the shades at a sloping position.

EDMUND H. LUNKEN.
